(57) **CLAIM**

The ornamental design for a display device for camera, as shown and described.

DESCRIPTION

FIG. 1 is a front perspective view of a display device for camera showing my new design;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top plan view thereof;

FIG. 7 is a bottom plan view thereof;

FIG. 8 is a rear perspective view thereof; and,

FIG. 9 is another front perspective view thereof, showing the display device for camera in an environment wherein the display device for camera is combined with a camera.

The broken lines illustrating portions of the display device for camera are for environmental purposes only and form no part of the claimed design.

The shade lines in the figures show contour and not surface ornamentation.
